UNITED STATES PATENT OFFICE.

PHILIP H. YAWMAN, OF ROCHESTER, NEW YORK, ASSIGNOR TO YAWMAN & ERBE MANUFACTURING COMPANY, OF ROCHESTER, NEW YORK, A CORPORATION OF NEW YORK.

PAPER-FILE.

1,022,456.

Specification of Letters Patent.

Patented Apr. 9, 1912.

Application filed November 25, 1907. Serial No. 403,705.

To all whom it may concern:

Be it known that I, PHILIP H. YAWMAN, of Rochester, in the county of Monroe and State of New York, have invented certain new and useful Improvements in Paper-Files; and I do hereby declare the following to be a full, clear, and exact description of the same, reference being had to the accompanying drawings, forming a part of this specification, and to the reference-numerals marked thereon.

My present invention relates to paper files, and particularly to the type employing a pair of posts upon which the sheets are impaled and a pair of coöperating members, usually in the form of an arch, movable simultaneously relatively thereto and upon which the upper sheets are transferred to render the lower ones accessible, and my invention has for its object to provide an improved tension device for the movable arches which will operate to retain them in or out of engagement with the posts when moved to either of these positions by the operator.

My improvements are further directed toward the construction and arrangement of the coöperating parts of the posts and arches.

To these and other ends this invention consists in certain improvements and combinations of parts all as will be hereinafter more fully described, the novel features being pointed out in the claims at the end of the specification.

In the drawings: Figure 1 is a top plan view of a paper file embodying my invention. Fig. 2 is a side elevation thereof. Fig. 3 is a bottom view of the device with the cover plate removed. Fig. 4 is a vertical section through the impaling posts taken on the line 4—4 of Fig. 1, and Fig. 5 is a vertical central section on the line 5—5 of Fig. 1.

Similar reference numerals in the several figures indicate similar parts.

In the device illustrated 1 indicates a base member provided with an eye 2 by means of which it may be hung upon a nail or hook and which is usually secured at the end of a board or backing by screws extending through the apertures 3, for which reason the bottom is preferably made flat, and the whole may be conveniently constructed by casting. On its under side the base is pro-

vided with a recess or chamber 4 covered by a plate 5 engaging against lugs 6 and held in position flush with the bottom of the base by a screw 7 threaded into a lug 8 within the chamber. The impaling posts 9 are preferably constructed of tubular stock and extend perpendicularly to the base or backing and parallel to each other at a suitable distance apart, according to the size of the papers to be accommodated. Their lower ends pass through the base and are secured by the expanded portions 10 on either side, while their upper ends are cut obliquely to form lateral openings 11 (in the present instance upon opposite sides). Opposite said openings and communicating therewith are arranged transversely extending apertures 12 in the wall of the tubes at the ends of the posts. The arches 13 are journaled in bosses 14 in the base member and also preferably in the cover plate 5, as at 15, to extend within the chamber 4 and to rotate upon axes parallel with the impaling posts and, in the present instance, to each other. They are preferably made of wire and their free ends are reduced eccentrically at 16, as shown in Figs. 2 and 4, so as to engage and be accommodated within the openings 11 and at the same time provide shoulders 17 to effectually cover the points 18 of the posts, which if allowed to project, would engage the papers while being slipped from the arches thereon. By engagement with these shoulders, the ends of the posts also serve to support the arches when downward pressure is applied thereto, and prevent them from being bent out of alignment. In my construction the one member thus forms a substantial continuation of the other and in order to preserve the rigidity of the connection I provide the ends of the arches with lateral projections in the form of pins 19 which engage within the apertures 12, and which may be conveniently punched partially out from the material of the member. The lower ends of the arches being journaled in the cover plate, as well as extending through a reinforced portion of the base, afford an extended bearing and promote a uniform movement that will bring the coöperating devices at the free ends always into correct position for engagement with the posts.

Rigidly attached to the portions of the arches extending through the chamber and

forming parts thereof are plates 20 to which are pivoted the opposite ends of a rod 21 connecting the arches for simultaneous movement in opposite directions, it being desirable that they move apart rather than toward each other for purposes of convenience. Likewise pivoted to each arch, through the medium of the plates, at points normally lying upon the same side of the plane of their axes is a tension member 22 which in the present instance is under compression and normally retains the arches in yielding engagement with the posts. I prefer to form this tension member from a spring wire looped or bent, as shown, at one or more points transversely to its general extent and having all its parts in the same plane, whereby it is rendered flat and easily accommodated within the chamber, allowing the latter to be made shallow to reduce the general bulk of the device as a whole. The elasticity of these looped portions provides ample energy and when the operator desires to attach or remove a paper he simply grasps one of the arches and rotates it away from the post, the other moving correspondingly and flexing the spring as its points of attachment are moving in opposite directions. As soon as these points of attachment have moved beyond the dead center, that is, to the opposite side of the plane of the axes, the said member or spring will continue the movement until one of the plates engages one of the lugs 6 on the base as a limit, as shown in dotted lines in Fig. 3. The arches will then be retained in such open position until moved back by the operator and the posts will be free and accessible.

40 I claim as my invention:

1. In a paper file, the combination with a base member and an impaling post mounted thereon having a lateral opening at its upper end and an aperture arranged opposite said opening, of an arch rotatably mounted on the base to move upon an axis parallel to the post and having its free end arranged to engage within the opening in the latter, said outer end being provided with a lateral projection removed from the extremity thereof and cooperating with the aperture in the post, the extremity of the arch beyond the projection having a lateral bearing against the post.

55 2. In a paper file, the combination with a base member and an impaling post mounted thereon provided with a lateral opening near its upper end the upper edges of the walls of said opening being terminated in a plane

oblique to the post to form an impaling point, of an arch rotatably mounted on the base to move upon an axis parallel to the post into engagement at its free end within the opening in the latter, and provided with a square overhanging shoulder adjacent said end engaging over the impaling point of the post.

3. In a paper file, the combination with a base member and an impaling post mounted thereon having a lateral opening at its upper end, of an arch rotatably mounted on the base to move upon an axis parallel to the post and having its free end reduced to constitute an eccentric projection engaging within the opening in the latter, and forming a shoulder covering the upper end of the wall of the opening.

4. In a paper file, the combination with a base member and a pair of impaling posts mounted thereon, of a pair of arches rotatably mounted on the base to coöperate with the impaling posts and connected for simultaneous movement, and a tension member connected to both arches at points both of which normally lie on the same side of the plane defined by the axes of rotation of the arches and are removed or spaced from the said axes to rotate about the latter.

5. In a paper file, the combination with a base member and a pair of impaling posts mounted thereon, of a pair of arches connected for simultaneous movement, rotatably mounted on the base to coöperate with the impaling posts and having their movement in one direction limited by engagement with said posts, a plate secured to one of the arches, a stop on the base adapted to be engaged by said plate for limiting the movements of the arches in the other direction and means pivotally interlocked with both arches at points removed from their axes of rotation for exerting a tension thereon.

6. In a paper file, the combination with a base member and a pair of impaling posts mounted thereon, of a pair of arches rotatably mounted on the base to coöperate with the impaling posts and connected for simultaneous movement, and a tension member pivotally connected to both arches at points removed from their axes of rotation the said points being located upon one side of the plane of the axes of the arches when the latter are closed against the posts and upon the other side when they are open.

PHILIP H. YAWMAN.
